CLAIM

The ornamental design for an anti-theft threaded cap, as shown and described.

DESCRIPTION

FIG. 1 is a front and top side perspective view of an anti-theft threaded cap embodying our new design;

FIG. 2 is a top plan view thereof;

FIG. 3 is a front elevational view thereof;

FIG. 4 is a bottom plan view thereof;

FIG. 5 is a front and top side perspective view of the anti-theft threaded cap of FIG. 1, showing only a lid portion;

FIG. 6 is a top plan view of the lid portion;

FIG. 7 is a front elevational view of the lid portion;

FIG. 8 is a bottom plan view of the lid portion;

FIG. 9 is a front and top side perspective view of the anti-theft threaded cap of FIG. 1, showing only a base portion;

FIG. 10 is a top plan view of the base portion;

FIG. 11 is a front elevational view of the base portion;

FIG. 12 is a bottom plan view of the base portion;

FIG. 13 is a cross sectional view of the anti-theft threaded cap taken along line 13—13 in FIG. 2; and,

FIG. 14 is a perspective view of four of the anti-theft threaded caps as used, for example, on license plate hardware.

All features illustrated in phantom line are expressly disclaimed and form no part of the claimed design.
